UNITED STATES PATENT OFFICE.

JOSIAH F. FRENCH, OF PHILADELPHIA, PENNSYLVANIA.

HANDLE FOR FILES AND OTHER TOOLS.

SPECIFICATION forming part of Letters Patent No. 285,987, dated October 2, 1883.

Application filed August 24, 1883. (No model.)

To all whom it may concern:

Be it known that I, JOSIAH F. FRENCH, a citizen of the United States, residing in Philadelphia, Pennsylvania, have invented certain 5 Improvements in Handles for Files and other Tools, of which the following is a specification.

My invention consists of a handle constructed for secure attachment to the tang or stem of a file or other tool, substantially as described 10 hereinafter.

In the accompanying drawings, Figure 1 is a view, mainly in section, and drawn to an enlarged scale, of my improved handle for files and other tools; Fig. 2, a view showing the 15 tang of a file or other tool prepared for attachment to the handle; Fig. 3, a transverse section of Fig. 1 on the line 1 2. Fig. 4 is a sectional view, illustrating a modification of my invention; and Fig. 5, a view showing the 20 application of the handle to a file or other tool which has no abrupt shoulder.

Into an orifice in the wooden portion A of the handle is driven a metal tube, B, made, preferably, of cast-iron annealed, a portion of 25 the tube being made octangular in the present instance, as shown in Fig. 3, to prevent it from turning in the orifice; but the tube may have a fin, and may be otherwise constructed externally to prevent it from turning. The 30 tube B is contracted and threaded internally at x, and is adapted to that portion of the tang D of a file or other tool which has parallelly-threaded edges m m, as shown in Fig. 2, a feature which forms no part of my present in- 35 vention, and which I do not claim in this application, as it forms the subject of an application for a patent filed by me August 27, 1883, Serial No. 104,858. The tube B has a flange, a, which is in contact with the end of the 40 wooden portion of the handle, and into the latter is driven and secured a ferrule, G, having an internal circular flange, b, between which and the outer end of tube B intervenes the flange h of the ring H, the latter projecting 45 beyond the end of the ferrule.

In screwing the above-described handle to its place the tube serves as a nut and the

outer edge of the ring H will be brought to bear on the shoulder m' m' of the tang, and in tightening the handle the ring will not turn, 50 but the end of the tube will bear and turn, against the small end of the ring, the latter thus serving as a washer when the final tightening takes place.

The object of the internal flange, b, of the 55 ferrule in conjunction with the flange h of the ring is to permanently connect the latter to the handle, and this may be done in ways other than that described. For instance, the ring H may be without a flange, as shown in Fig. 4, 60 and a pin or pins, w, may be passed through and secured to the ferrule and project into a circular groove in the ring.

Whatever plan may be adopted of confining the ring H to the ferrule the connection 65 should be loose, as shown in the drawings, so that the handle can be turned independently of the ring and so that the latter can accommodate itself to any inequalities on the shoulders of the file and other tool. 70

I prefer to make a ball-and-socket bearing at the junction of the ring with the end of the tube, a feature, however, which forms no part of my present invention. The handle is not restricted in its application to files or other 75 tools having abrupt shoulders. It may be fitted, for instance, to a file or other tool having a tang, as shown in Fig. 5, in which case the ring will bear against the tapering portion of the tang. 80

I claim as my invention—

A tool-handle in which a threaded tube, B, driven into the wooden portion of the handle, and a ferrule, G, secured to the same, are combined with a ring, H, loosely connected to the 85 ferrule, substantially as set forth.

In testimony whereof I have signed my name to this specification in the presence of two subscribing witnesses.

JOSIAH F. FRENCH.
